UNITED STATES PATENT OFFICE.

RAYMOND H. OLLEY, OF SYRACUSE, NEW YORK, ASSIGNOR, BY MESNE ASSIGNMENTS,
TO GEORGE CUTTER COMPANY, OF SOUTH BEND, INDIANA, A CORPORATION OF
INDIANA.

PANEL-BOARD.

1,202,091.

Specification of Letters Patent. Patented Oct. 24, 1916.

Application filed October 6, 1910, Serial No. 585,598. Renewed February 21, 1914. Serial No. 820,324.

To all whom it may concern:

Be it known that I, RAYMOND H. OLLEY, of Syracuse, in the county of Onondaga and State of New York, have invented a new and useful Panel-Board, of which the following is a specification.

My invention relates to panel boards and has for its object a particularly simple and efficient arrangement of conducting bars and terminals thereof, and it consists in the combinations and constructions hereinafter set forth and claimed.

In describing this invention reference is had to the accompanying drawing in which like characters designate corresponding parts in all the views.

Figure 1 is a plan, partly in section, of a panel board embodying one form of my invention. Figs. 2 and 3 are sectional views taken respectively on lines "A—A" and "B—B", Fig. 1. Fig. 4 is an isometric view of a portion of the panel board, parts being omitted. Fig. 5 is a vertical sectional view of parts seen in Fig. 4. Fig. 6 is a detail view of the insulating rings of the terminal posts.

This panel board comprises, generally, a base or panel board proper which is usually a slab of slate or marble, a plurality of conductors supported by the base, one above the other when the panel board is in horizontal position, the conductors being adapted to be connected in different circuits, terminals arranged in a series along the conductors on the same side of the base as said conductors and being designed to be connected in other circuits, and means for connecting the terminals to any of the conductors.

This invention is here shown as embodied in a meter panel board, and two sets of conductors are shown arranged parallel to each other and adapted to be connected in circuit with the meters and the terminals are arranged in a row midway between the sets of conductors and are designed to be connected in the load circuits.

1 is the base of the panel board; 2 and 3 are the main or supply conductors connected to the bus bars 4 and 5; 6 is the neutral main conductor connected to the bus bars 7, a switch 8 and fuses 9 being interposed between the mains 2, 3 and 6 and the bus bars 4, 5 and 7. The bus bars 4 and 5 are connected through fuses 10 and 11 respectively

to terminals 12 and 13, and these terminals 55 12 and 13 are connected through wires 14 and 15 to meters 16 and 17 located on opposite margins of the base. 18 and 19 are sets of conductors arranged one above the other when the panel board is in horizontal position and connected respectively by wires 20 and 21 to the meters 16 and 17 on opposite sides of the base 1. Of course, when the panel board is in use it is usually in vertical position and the bars 18 and 19 are arranged 65 one in front of the other. The term "one above the other when the panel board is in horizontal position" is employed merely for convenience. The wires 20 and 21 are connected to the ends of the bars 18 and 19 at 70 22 and 23 and the end portions of alternating bars of each set are deflected laterally in opposite directions (Figs. 1 and 4) in order to facilitate the connection thereto of the wires 20 and 21. The meters 16 and 17 are connected with wires 24 and 25 respectively connected to the neutral main bar 7. 75

26 and 27 are terminals arranged in a series extending along the bars 18 and 19 and preferably midway between the bars 18 and 19. 80 The terminals 26 and 27 alternate with each other and are connected respectively to bars 28 and 29 connected to terminals 30 and 31 through fuses 32 and 33, each terminal 30 or 31 being connected to one side of a load circuit 34 or 35, the opposite side of which is connected to a terminal 36 or 37 which is connected to a bar 38 or 39 extending parallel to the meter bars 18 and 19, the bars 38 and 39 being connected to the neutral bus bar 7. 90 Suitable fuses 40 and 41 are also interposed between the terminals 36 and 37 and the bars 38 and 39. 95

Any one or all of the terminals 26 and 27 may be connected to any one of the meter bars 18 or 19 by interchangeable members which are duplicates so that it is not necessary to furnish several sizes of connecting members with the panel board in order to meet the various changes of connections that it may be desirable to make. 10

The panel board just described is of double construction and the parts on one side thereof designated by odd numbers are duplicates of the parts on the opposite side thereof designated by even numbers. However, the panel board may be of single construction and as the parts of one half of the panel

board are duplicates of those on the other half thereof, a description of one set of parts will be sufficient for both and in this description those bearing the even numbers will be referred to.

The bars 18 or 19 are supported by pillars projecting from the base, each comprising a bolt 42 (Fig. 2), a sleeve of insulation 43 encircling the bolt, spacing rings 48 of insulation encircling the sleeve 43 and interposed between the lowermost bar 18 and the front face of the base and between the bars 18, the bars 18 being separated by an open space between the pillars for facilitating the connection of such bars to the terminals 26 and 27 as hereinafter described. The bolt 42 extends through the base, and is secured thereto by a nut 45 on the rear side of the base, and the bolt 42 and the sleeve 43 extend through perforations in the bars 18 or 19, the head of the bolt overlying the topmost bar.

Each of the terminals 26 or 27 is a post rising from the base and consisting of a bolt 46 extending to the rear side of the base and held in position by a nut 47, spacing rings 48 encircling the bolt one above the other and adapted to receive between them the connecting members 49 to be described, means for clamping the rings 48 together, and means for limiting the separation of the rings to approximately the thickness of the contiguous part of one of the connecting members 49 so that but one connecting member 49 at a time can be electrically connected to one terminal. The edges of the abutting faces of the rings 48 are located in substantially the horizontal planes of the meter bars 18 and 19, and the edges of the peripheries of the rings are chamfered (Figs. 2 and 3) for facilitating the insertion of the connecting members. Preferably the terminals include insulating means encircling the rings 48 and having passages which expose the edges of the abutting faces thereof. As here illustrated this insulating means consists of a plurality of sections 50 having passages 51 in their abutting ends, the sections 50 being adapted to turn about the axis of the terminal and being provided with interlocking means for causing all of such sections to turn together. The interlocking means consists of mortise and tenon joints 52, Figs. 2 and 6, extending lengthwise of the terminals and arranged diametrically opposite to the passages 51, the tenons also serving to prevent the insertion of a connecting member 49 between the rings 48, as for instance when a member 49 is connecting one of the bars 18 with one terminal, as shown in Fig. 2, and an attempt is made to connect with the same terminal, another member 49 which is engaged with the opposite bar 19.

65 The spacing rings 48 and also the insu-

lating rings 50 are clamped together by a nut 53 turning on the upper end 54 of the bolt 46 and the separation of the spacing rings 48 is limited to approximately the thickness of one of the connecting members 49 by a shoulder 55 at the upper end of the bolt 46. The nut 53 is preferably provided with a handle 56 of insulating material.

The bolt 46 is held upright by a sleeve 57 of insulation interposed between the base 1 of the panel board and the lowermost insulating ring or section 50, said sleeve having an internal shoulder 58 against the upper side of which turns a jam nut 59. However, the insulating sections may be omitted, as seen in Figs. 4 and 5, and the terminal post 46 supported by a nut 60 at the upper end thereof and by the head 61 of the bolt on the rear side of the base.

Preferably a plurality of pillars supporting the meter bars 18 and 19 and a plurality of terminal posts are reinforced in their support by braces 62, Figs. 1 and 2, located at the upper ends of said pillars and terminal posts, each brace 62 being here shown as formed to bridge opposite pillars supporting the bars 18 and 19 and one terminal 26 and one terminal 27, the pillars and terminals so bridged being arranged at the corners of a rectangular figure described by straight lines connecting in succession the centers of said pillars and terminals.

Each connecting member 49 by which any one of the terminal posts may be connected to any one of the meter bars 18 or 19, as here shown, consists of a strip of metal having at one end a bifurcation 63 adapted to be slidably inserted between two of the spacing rings 48 through one of the passages 51, the opposite end portion of such strip being bent upon itself at 64 to form a loop extending at an angle from the major part of the connecting member, the free end of said loop being extended toward the free end of said major part into a position parallel to said major part and constituting a yielding arm of less length than said major part, such arm and major part forming means for straddling horizontally and clamping a meter bar 18 or 19. A handle 65 of insulation is engaged with said loop and with the upper face of said major part, and is secured by suitable clamping means, as a screw, to the branch of said loop contiguous to said major part, such handle being provided with a surface 66, such surface being usually inclined. The combined thickness of the major part of the connecting member and the thickest part of said portion of the handle provided with the inclined surface is less than the distance between two of the meter bars 18 or 19 for permitting such portion of the handle to pass between two of the meter bars when the connecting member is arranged to straddle one of the meter bars,

- but the combined thickness of the parallel portions of the connecting members and said portion of the handle having the inclined surface is greater than the distance between 5 two of the meter bars 18 or 19 and thus an imperfect connection between the connecting member and the meter bars is prevented, as when the parallel portions of the connecting member do not straddle the meter bar.
- 10 The arrangement of the meter bars and the terminals for the load circuit bars is particularly advantageous in that any terminal may be connected on the upper side of the base to the meter bars at a plurality 15 of points at intervals lengthwise of the terminal, and the described means for electrically connecting said meter bars and terminals is advantageous in that like connecting members serve to make all of the de- 20 sired electrical connections between said bars and terminals, and said members are readily and quickly forced into or out of operative position by a single sliding move- 25 ment.
- What I claim is:
1. In a panel board, a base, a plurality of conductors supported by the base one above the other when the panel board is in horizontal position, the conductors being adapt- 30 ed to be connected in different circuits, terminals arranged in a series along the conductors and designed to be connected respec- 35 tively in other circuits, the terminals being spaced equidistant from all of the conductors, and means for connecting any one of the terminals to any one of the conductors, substantially as and for the purpose set forth.
  2. In a panel board, a base, a plurality of 40 conductors supported by the base one above the other when the panel board is in horizontal position, the conductors being adapt- 45 ed to be connected in different circuits, terminals arranged in a series along the con- ductors on the same side of the base as said 50 conductors and designed to be connected respec- 55 tively in other circuits, the terminals being spaced equidistant from all of the conductors, and interchangeable means for con- 60 necting the terminals to any one of the conductors, said means extending parallel to the base, substantially as and for the purpose de- 65 scribed.
  3. In a panel board, a base, a set of con- 70 ductors supported by the base one above the other when the panel board is in horizontal position, a second set of conductors sup- 75 ported by the base one above the other and being opposed to the first set of conductors, the conductors being adapt- 80 ed to be connected in different circuits, terminals ar- 85 ranged in a series on the same side of the base as the conductors and between the sets of conductors, the terminals being designed 90 to be connected respectively in other circuits,

and means for connecting the terminals to any of the conductors, substantially as and for the purpose set forth.

4. In a panel board, a base, a set of conductors supported by the base, one above the other when the panel board is in horizontal position, a second set of conductors supported by the base one above the other parallel to the first set, the conductors being adapted to be connected in different circuits, 70 terminals arranged in a series on the same side of the base as the conductors and located about midway between the sets of conductors, the terminals being designed to be connected respectively in other circuits, and 80 interchangeable means for connecting any one of the terminals to any of the conductors, substantially as and for the purpose de- 85 scribed.

5. In a panel board, a base, a plurality of 8 conductors supported by the base one above the other when the panel board is in horizontal position, the bars being adapted to be connected in different circuits, terminal posts rising from the base to at least the height of the uppermost bar and ar- 9 arranged in a series along the conducting bars on the same side of the base as said bars, the terminal posts being designed to be connected respectively in other circuits, and means for connecting the terminal posts to any of the bars, substantially as and for the purpose specified.

6. In a panel board, a base, a plurality of 90 conductors supported by the base one above the other when the panel board is in horizontal position, terminal posts rising from the base and arranged in a series along the conducting bars on the same side of the base as said bars, the terminal posts being spaced equidistant from the bars and designed to be connected respec- 95 tively in other circuits, and interchangeable means for connecting any one of the terminal posts to any one of the conducting bars, substantially as and for the purpose set forth.

7. In a panel board, a base, two parallel sets of conducting bars supported by the base, each set comprising bars parallel to each other, the bars being spaced apart from the base and adapted to be connected in different circuits, terminal posts rising from the base and arranged in a row about mid- 100 way between the sets of conducting bars and an interchangeable member for connect- 105 ing any one of the terminal posts to any one of the conducting bars, substantially as and for the purpose described.

8. In a panel board, a base, a set of con- 110 ducting bars supported by the base one above the other when the panel board is in horizontal position, a second set of conductin- 115 bars supported by the base one above th other and parallel to the first set, the con-

ducting bars being adapted to be connected in different circuits, terminal posts rising from the base and arranged in a series extending about midway between the sets of 5 conducting bars and designed to be connected respectively in other circuits, and interchangeable means for connecting any one of the terminal posts to any one of the conducting bars, substantially as and for the 10 purpose specified.

9. In a panel board, a base, a plurality of conductors supported by the base one above the other when the panel board is in horizontal position, the conductors being 15 adapted to be connected in different circuits, terminals arranged in a series along the conductors on the same side of the base as said conductors and being designed to be connected in other circuits, and members 20 for connecting the terminals to any of the conductors, each terminal comprising a post, spacing rings encircling the post one above the other, means for clamping the rings together, any two of the rings being 25 adapted to receive a connecting member between them, and means for limiting the separation of the spacing rings to approximately the thickness of the contiguous part 30 of the connecting member, substantially as and for the purpose described.

10. In a panel board, a base, a plurality of conducting bars supported by the base one above the other when the panel board is in horizontal position, the bars being 35 adapted to be connected in different circuits, terminals arranged in a series along the conducting bars on the same side of the base as said bars, the terminals being designed to be connected respectively in other 40 circuits, and members for connecting the terminals to any of the bars, each terminal comprising a post rising from the base, spacing rings encircling the post one above the other, and each being of substantially 45 the same thickness as the spaces between two of the bars and being alined horizontally with such spaces respectively, means for clamping the rings together, any two of the rings being adapted to receive a connecting member between them, and means for limiting the separation of the spacing rings to approximately the thickness of the contiguous part of the connecting member, substantially as and for the purpose 50 specified.

11. In a panel board, a base, a plurality of conducting bars supported by the base one above the other when the panel board is in horizontal position, terminals arranged 55 in a series along the conducting bars on the same side of the base as said bars, the terminals being spaced equidistant apart from the bars and designed to be connected respectively in other circuits, and interchangeable 60 members for connecting any one of the

terminals to any one of the conducting bars, each terminal comprising a post having a threaded portion, spacing rings encircling the post one above the other, and a nut turning on the threaded portion of the post in one direction for clamping the rings together, any two of the rings being adapted to receive one of the connecting members between them, and the post having a shoulder for limiting the separation of the spacing 75 rings and the movement of the nut in the opposite direction to approximately the thickness of the contiguous part of the connecting member, substantially as and for the 80 purpose set forth.

12. In a panel board, a base, conductors supported by the base parallel to each other and in the same plane, the conductors being adapted to be connected in different circuits, a terminal arranged between the conductors 85 and including spacing rings one above the other, the edges of the abutting faces of the rings being in substantially the same plane as the conductors, and means for connecting the conductors with the terminal, said means 90 being designed to be inserted between the rings, and the terminals being provided with means for preventing connection being made between the terminal and either conductor when said terminal is connected to one of the 95 conductors, substantially as and for the purpose described.

13. A binding device for panel boards comprising a post, spacing rings encircling the post one above the other, and insulating 100 sections encircling the rings one above the other and having passages exposing the edges of the abutting end faces of the rings, and means for locking the sections together, said means permitting the sections to move 105 endwise relatively to each other and causing the same to turn as a unit about the axis of the post, in combination with a connecting member for entering any one of the passages and between the rings exposed through said 110 passage, substantially as and for the purpose set forth.

14. A binding device for panel boards comprising a post, spacing rings encircling the post one above the other, and insulating 115 sections encircling the rings one above the other and having passages between said sections exposing the edges of the abutting end faces of the rings, contiguous sections being connected by a mortise and tenon extending 120 lengthwise of the post and located diametrically opposite to the passages, in combination with a connecting member for entering any one of the passages and between the rings exposed through said passage, substantially as and for the purpose described.

15. In combination, a metallic connecting member, and a binding device comprising a post, metallic spacing rings encircling the post one above the other, insulating sections 125 130

encircling the rings one above the other and having passages at intervals lengthwise of the post, any one of the passages being adapted to receive the connecting member, means for clamping the rings together, any two of the rings being adapted to receive the connecting member between them, and means for limiting the separation of the spacing rings to approximately the thickness of the contiguous part of the connecting member, substantially as and for the purpose specified.

16. In combination, a metallic connecting member, and a binding device for panel boards comprising a post having a threaded portion, metallic spacing rings encircling the post one above the other, insulating sections encircling the rings one above the other and having passages between said sections exposing the edges of the abutting end faces of the rings, any one of the passages being adapted to receive the connecting member and any two of the rings being adapted to receive the connecting member between them, and a nut screwing on the threaded portion of the post in one direction against the rings and the sections, the post being provided with a shoulder for limiting the movement of the nut in the opposite direction to approximately the thickness of the connecting member, substantially as and for the purpose set forth.

17. In combination, a metallic connecting member, and a binding device for panel boards comprising a post having a threaded portion, metallic spacing rings encircling the post one above the other, insulating sections encircling the rings one above the other, and having passages exposing the edges of the abutting end faces of the rings, contiguous sections being connected by a mortise and tenon extending lengthwise of the post and arranged diametrically opposite to said passages, any two of the rings being adapted to receive the connecting member between them, such connecting member entering through one of the passages, and a nut turning on the threaded portion of the post in one direction against the rings and the insulating sections, the post being provided with a shoulder for limiting the movement of the nut in the opposite direction to approximately the thickness of the contiguous part of the connecting member, substantially as and for the purpose specified.

18. In a panel board, a base, a plurality of conducting bars supported by the base one above the other when the panel board is in horizontal position, the bars being adapted to be connected in different circuits, terminals arranged in a series along the bars on the same side of the base as said bars and being designed to be connected respectively in other circuits, and means for connecting the bars to any one of the terminals, each

terminal comprising a post rising from the base, metallic spacing rings encircling the post one above the other, insulating sections encircling the rings one above the other and having passages at intervals lengthwise of the post for receiving the connecting means, and means for clamping the rings together, substantially as and for the purpose specified.

19. In a panel board, a base, a plurality of conducting bars supported by the base one above the other when the panel board is in horizontal position, the bars being adapted to be connected in different circuits, terminals arranged in a series along the bars on the same side of the base as said bars and being designed to be connected respectively in other circuits, and means for connecting the bars to any one of the terminals, each terminal comprising a post rising from the base, metallic spacing rings encircling the post one above the other, insulating sections encircling the rings one above the other and having passages at intervals lengthwise of the post for receiving the connecting means, means for clamping the rings together, any two of the rings being adapted to receive between them one of the connecting means, and means for limiting the separation of the spacing rings to approximately the thickness of the contiguous part of the connecting means, substantially as and for the purpose set forth.

20. In a panel board, a base, a set of conducting bars supported by the base one above the other when the panel board is in horizontal position, a second set of conducting bars supported by the base one above the other parallel to the first set, the conducting bars being adapted to be connected in different circuits, terminals arranged in a series along the conducting bars on the same side of the base as said bars and midway between the sets of bars, the terminals being designed to be connected respectively in other circuits, and interchangeable means for connecting any one of the terminals to any one of the conducting bars, each terminal comprising a post rising from the base and having a threaded portion, spacing rings encircling the post one above the other, insulating sections encircling the rings and having passages between said sections exposing the edges of the abutting end faces of the rings and aligned with the edges of the bars, the rings being adapted to receive between them one of the connecting means, and contiguous insulating sections being connected by a mortise and tenon extending lengthwise of the post and located diametrically opposite to the passages, and a nut turning on the threaded portion of the post in one direction against the spacing rings and the insulating sections, the post being provided with a shoulder for limiting the

movement of the nut in the opposite direction to approximately the thickness of the contiguous part of the connecting means, substantially as and for the purpose described.

21. In a panel-board, a base, a plurality of conductors supported by the base and arranged one above the other in a row extending at right angles to the base, the conductors being adapted to be connected in different circuits, terminals arranged at right angles to the base in a row along the conductors on the same side of the base as said conductors and at one side of said conductors, the terminals extending crosswise of the planes of a plurality of the conductors, the edges of the conductors being spaced apart from the terminals, and means for connecting the terminals to any of the conductors, substantially as and for the purpose described.

22. The combination of a conducting bar and a terminal post arranged at right angles to each other and spaced apart; with a connecting member for electrically connecting said bar and post, the connecting member consisting of a strip of metal having one end portion folded toward an intermediate portion of the member to produce an arm of less length than the opposing major part of the connecting member, opposing surfaces of said arm and the major part of the connecting member slidably engaging opposite sides of the conducting bar, and the end of the major part of the connecting member coating with the terminal post, said connecting member being movable endwise into simultaneous engagement with the conducting bar and the terminal post, substantially as and for the purpose specified.

23. The combination of a conducting bar and a terminal post arranged at right angles to each other and spaced apart, the post being provided with opposing metallic sleeves; with a connecting member for electrically connecting said bar and post, the connecting member consisting of a strip of metal having one end portion folded to form a loop extending at an angle from the major part of the connecting member, the free end of the loop being extended toward the free end of said major part and being substantially parallel with said major part and constituting a yielding arm of less length than said major part, opposing surfaces of said arm and major part slidably engaging opposite faces of the conducting bar, and the free end of said major part being bifurcated to receive the terminal post and having its opposite faces slidably engaging the abutting surfaces of said sleeves, said connecting member being movable endwise into simultaneous engagement with the conducting bar and the metallic sleeves, substantially as and for the purpose described.

24. The combination of a conducting bar and a terminal post arranged at right angles to each other and spaced apart, the post being provided with opposing metallic sleeves; with a connecting member for electrically connecting said bar and post, the connecting member consisting of a strip of metal having one end portion folded to form a loop extending at an angle from the major part of the connecting member, the free end of the loop being extended toward the free end of said major part and being substantially parallel with said major part and constituting a yielding arm of less length than said major part, opposing surfaces of said arm and major part slidably engaging opposite faces of the conducting bar, and the free end of said major part being bifurcated to receive the terminal post and having its opposite faces slidably engaging the abutting surfaces of said sleeves, a handle of insulation engaged with said loop and with the face of said major part opposite to the face of said part opposed to said arm, and means for securing the handle to the branch of the loop contiguous to said major part, substantially as and for the purpose set forth.

25. In a panel board, a base, a plurality of conducting bars supported by the base one above the other when the panel board is in horizontal position, a terminal post rising from the base, and a member for connecting any one of the bars and the terminal post, said member having means for engaging opposite sides of a bar, and a block of insulation for entering between the bars, the combined thickness of the portion of the block entering between the bars and the engaging means of said member being greater than the distance between two of such bars, substantially as and for the purpose set forth.

26. In a panel board, a base, a plurality of conducting bars supported by the base one above the other when the panel board is in horizontal position, a terminal post rising from the base, and a member for connecting any one of the bars and the terminal posts, said member having means for engaging opposite sides of a bar, and a block of insulation for entering between the bars, the combined thickness of the portion of the block entering between the bars and the engaging means of said member being greater than the distance between two of such bars, and said portion of the block having an inclined surface, substantially as and for the purpose described.

27. In a panel board, a base, a plurality of conducting bars supported by the base one above the other when the panel board is in horizontal position, the bars being connected in different circuits, pillars projecting from the base for supporting the conducting bars and including spacing rings of

insulation located between the bars at intervals, terminals arranged in a series along the bars and designed to be connected respectively in other circuits, and members for connecting the terminals to any one of the conducting bars, each connecting member including a strip of metal having means at one end for engaging one of the terminals, the opposite end portion of the strip being bent upon itself into a position parallel to the major part of such strip and together therewith forming means for straddling horizontally any one of the conducting bars, the connecting member being designed to be passed crosswise of the conducting bars into engagement with one of the terminals and to receive between its parallel portions one of such conducting bars, substantially as and for the purpose specified.

28. In a panel board, a base, a plurality of conducting bars supported by the base one above the other when the panel board is in horizontal position, the bars being adapted to be connected in different circuits, terminal posts rising from the base and arranged in a series along the conducting bars on the same side of the base as said bars, the terminal posts being designed to be connected respectively in other circuits, and members for connecting the terminal posts to any of the bars, each member comprising a strip of metal folded upon itself into a position parallel to the major part of the strip and together therewith forming means for receiving and clamping one of the conducting bars, substantially as and for the purpose set forth.

29. In a panel board, a base, a plurality of conductors supported on the base one above the other when the panel board is in horizontal position, the conductors being adapted to be connected in different circuits, terminals arranged in a series along the conductors on the same side of the base as said conductors and being designed to be connected in other circuits, and members for connecting the terminals to any of the conductors, each terminal comprising a post, spacing rings encircling the post one above the other, means for clamping the rings together, any two of the rings being adapted to receive one of the connecting members between them, and means for limiting the separation of the spacing rings to approximately the thickness of one of the connecting members, and each connecting member comprising a strip of metal bifurcated at one end for entering between the spacing rings, the opposite end portion of the strip being folded upon the major part of the strip into a position parallel to such major part and together therewith forming means for receiving and clamping the conductors, substantially as and for the purpose described.

30. In a panel-board, a base, a plurality of flat relatively thin conductor bars extending lengthwise of the base and having their wider faces arranged parallel to the face of the base, said bars being connected in different circuits, a plurality of terminals in other circuits arranged in a row lengthwise of the base and at one side of a plane perpendicular to the face of the base and in which said conductor bars are located, and a plurality of duplicate connecting members for establishing all of the desired connections between said terminals and bars.

31. In a panel-board, a base, a plurality of flat relatively thin conductor bars extending lengthwise of the base and having their wider faces arranged parallel to the face of the base, said bars being connected in different circuits, a plurality of terminals of other circuits arranged in a row lengthwise of the base and at one side of a plane perpendicular to the face of the base and in which said conductor bars are located, and a plurality of duplicate connecting members for establishing the desired connections between the terminals and bars, said members being separable from the bars and terminals, and each adapted to establish electrical connection between any one of the terminals and a selected bar, substantially as and for the purpose described.

32. In a panel-board, a base, a plurality of conductor bars extending lengthwise of the base and located in a common plane perpendicular to the face of the base, said bars being connected in different circuits, a plurality of terminals of other circuits arranged in a row lengthwise of the base, and a plurality of duplicate connecting members for establishing all the desired connection between the terminals and bars, substantially as and for the purpose set forth.

33. In a panel-board, a base, a plurality of conducting bars extending lengthwise of the base and each connected in an individual meter circuit, a plurality of terminals of other circuits located on the same side of the base as the bars, and means for establishing electrical connection at one of a plurality of points at intervals lengthwise of each terminal and a selected bar.

34. In a panel-board, a base, a plurality of conducting bars extending lengthwise of the base and each connected in an individual circuit, a plurality of terminals of other circuits located on the same side of the base, members for establishing electrical connection between the bars and any one of the terminals, the connection with the terminal being made at one of a plurality of points located at intervals along the length of the panel, and means for preventing the establishment of a connection between any one of the bars and a second point on the terminal after one connection has been made.

35. In a panel-board, a base, a plurality of conducting bars extending lengthwise of the base and located in a common plane perpendicular to the face of the base, each of 5 said bars being connected in an individual circuit, a plurality of terminal posts arranged in a row lengthwise of the base and at one side of said bars, and each terminal extending perpendicular to the face of the 10 base and in a direction crosswise of the edges of the bars, and a plurality of duplicate connecting members for establishing all the desired connections between the terminals and bars.
- 15 36. In a panel-board, a base, a plurality of conducting bars connected in individual circuits, a plurality of terminals of other circuits, and members for establishing electrical connection between one or more of 20 these terminals and any one of the bars, each terminal comprising a post, and spacing rings associated therewith and movable lengthwise thereof a distance less than the 25 combined thickness of two of the connecting members.
37. In a panel-board, and in combination, a base, a terminal of a circuit of one class mounted on the board, a pair of conductor bars, each member of said pair being located 30 in an independent circuit of another class and said bars being arranged on opposite side of the terminal, and a connecting member for connecting either of the conductor bars to the terminal, said terminal includ- 35 ing a part having electrical conductivity for engaging with the connecting member, and a part of insulation having an opening for receiving the connecting member and a shield arranged to prevent the connecting member 40 from engaging the terminal when the connecting member is engaged with a bar other than that with which the opening of the part of insulation is aligned, whereby when the parts are arranged for permitting a con- 45 nection to be made between one conducting bar and the terminal a connection between the remaining conducting bar and terminal will be prevented, substantially as and for the purpose specified.
- 50 38. A panel-board comprising a base, a terminal located in a circuit of one class, a pair of conducting bars each located in an independent circuit of another class, said bars being respectively arranged on oppo-

site sides of the terminal, and a connecting 55 member, said terminal including a part having electrical conductivity for engagement by the connecting member, and a part of insulation rotatable about the part having electrical conductivity, said part of insulation having an intact portion for providing a barrier between the terminal and one conducting bar and having a slot for permitting a connection to be made between the other conducting bar and part having electrical 60 conductivity, substantially as and for the purpose set forth.

39. In a panel-board, the combination with two sets of conductor bars and a plurality of terminals arranged in a row be- 70 tween the two sets, and connecting members for establishing electrical connection between selected bars, and terminals, each of said terminals comprising a part having electrical conductivity, and a tubular part 75 of insulation surrounding the part having electrical conductivity, and provided with a plurality of transverse slots and an intact portion, said part of insulation being rotatable for interposing its intact portion between 80 the conducting bars of one set and the part having electrical conductivity, and for presenting its slots between the conductors bars of the other set and the part having electrical conductivity, substantially as and for 85 the purpose described.

40. In a panel-board, a base, a plurality of perpendicular terminals arranged in a row and spaced from one another, and including a part having electrical conductivity and an encircling part of insulation, sets 90 of conductor bars on opposite sides of the terminal, pillars supporting the bars, and brace plates offset from the base of the board, and each connected to a pair of pillars 95 and being provided with a pair of spaced apart openings for receiving the parts of insulation of a pair of terminals, substan- tially as and for the purpose specified.

In testimony whereof, I have hereunto 100 signed my name, in the presence of two attesting witnesses, at Syracuse, in the county of Onondaga, in the State of New York, this 30th day of September, 1910.

RAYMOND H. OLLEY.

Witnesses:

CARL H. BISSELL,
C. C. SCHOENECK.
